SHEET-METAL-DOOR CONSTRUCTION.

1,167,414.

Specification of Letters Patent. Patented Jan. 11, 1916.

Original application filed January 14, 1915, Serial No. 2,120. Divided and this application filed May 1, 1915. Serial No. 25,097.

To all whom it may concern:

Be it known that we, ALBERT LESLIE LAMBERT and ALFRED B. BELL, citizens of the United States, residing at Philadelphia, in the county of Philadelphia and State of Pennsylvania, have invented certain new and useful Improvements in Sheet-Metal-Door Constructions, of which the following is a specification.

10 Our invention relates to sheet-metal door construction and particularly to the construction of fireproof doors having rail and stile or frame members comprising parallel metallic plates, panels of glass, metal, or 15 other substance and molding members also usually being used.

The invention covered by our present application is a division of our application Serial No. 2120, filed January 14, 1915, for 20 panel door construction.

The invention covered herein particularly comprises means and a method for securing together the frame members of the door at the corners by the use of connecting members interposed between the outer sheets of the door at the corners and extending over the joints between the adjacent ends of the frame members, these connecting devices being so arranged as to enable the various 25 parts to be welded together effectively and with a minimum amount of heat; the result being to form a rigid connection between the connected sheets at the seam, in such manner that little or no shrinkage is experienced when the sheets of the door are 30 subsequently welded at their abutting edges, the tendency of the frame members to warp or become distorted because of the welding together of the same being largely overcome 35 by this construction.

In order that a clearer understanding of our invention may be had, attention is here- 40 by directed to the accompanying drawings forming part of this application illustrating the application of the method referred to and one embodiment of our improved construction.

In the drawings Figure 1 represents a 45 partial front elevation of a corner of a sheet-metal door, certain parts being shown in section to illustrate our improved "corner-box" construction, and Fig. 2 is a section on line 2-2 of Fig. 1, the upper plates

being shown separated from the lower members to illustrate the process before welding 55 has been carried out.

Referring to the drawings, I have illustrated a door comprising stiles and rails, together with one or more panels. In Fig. 1 a corner of the door is illustrated showing the vertical stile 1 and the top rail 2, the stiles and rails at each corner of the door being mitered at their ends to form abutting inclined edges 3 which are joined by the corner-box construction, which will 60 be more fully described hereinafter. The various frame members, as for example the stile 1, comprise parallel metallic sheets 4 and 5, which in the construction illustrated, form side members of the stile or other 65 frame member, asbestos or other fireproof material 6 being interposed between the plates. The outside sheets of the top rail are shown in Fig. 2 at 4' and 5'. A panel 7 is illustrated as being mounted in molding members 8, the flanges of which are 70 welded or otherwise secured to the flanges 9 of the side sheets of the stiles and rails, 75 as is more fully described in the application above referred to.

The corner-box construction, which I use in joining together the adjacent ends of the top and bottom rails and stiles, comprises a pair of channel-bars 10 and 11. As stated, the outside sheets 4 and 5 and 4' and 5' of 80 the stile 1 and the top rail 2 abut against each other at mitered or inclined edges 3. At each such joint, a channel-bar 10 is inserted between the sheets transverse to the same and a second channel-bar 11 is inserted 85 within the flanges of bar 10 and in a reverse direction to bar 10, so as to form a box-section with the same. The outside channel 10 is provided with raised welding spots 12 on the outer sides of its flanges, which spots 90 contact the inner surfaces of plates 5, 5' and 4, 4'. In Fig. 2 plates 5 and 5' are shown separated from members 1 and 2, in order to show welding spots 12. After welding, members 1 and 2 will contact plates 5 and 5'. The 95 flanges of the channel-bars and the outside plates of the rail and stile are then welded together by the application under sufficient welding pressure of the electrodes of a welding machine to the outer surfaces of the outside plates in line with the welding spots. 100 105

In this operation, the inner channel 11 acts as a support to prevent the plates from bending or crushing under the welding pressure. After the box constructions have been 5 welded into place at the joints between the stiles and rails, the seams 3 may be closed up by the usual method of gas or arc-welding. By the provision of the rigid construction described under the parts which are 10 welded, and by having the reinforcing members rigidly connected to the outside plates on each side of the seams, the shrinkage which usually results from the arc-welding of the seams is not obtained and consequently 15 the door remains nearly flat after the welding operation. In the assembling of the doors, the frame members are joined together, as described, after which the panels may be mounted in position by means of the 20 molding members which are then mounted in place and welded, resulting in a strong and uniform construction.

It will be understood that our invention 25 comprises the combination of structural elements in a door described, and also the method of assembling the same to join together the adjacent edges of the frame members of the door, which consists in positioning a channel-bar having raised welding 30 spots thereon, within the side sheets of the abutting frame members and transverse to

the same, positioning a metallic reinforcing or compression member between the flanges of the channel-bar referred to, welding the parts together and thereafter welding together 35 the seams or joints between the abutting edges of the side sheets of the frame members.

Having now particularly described our invention, what we claim and desire to protect by Letters Patent is as follows:

In a door, or similar construction, the combination of a pair of frame members, one transverse and the other longitudinal, having parallel metallic inner and outer sheets, 45 having abutting inclined ends welded together to form a corner of the structure, a channel bar within said sheets, extending transverse to the welded joints of the same and welded to sheets on both sides of the 50 joints and a channel bar within said first channel bar, in reversed position thereto, to form a box section with said first bar, substantially as set forth.

This specification signed and witnessed 55 this 28th day of April, 1915.

ALBERT LESLIE LAMBERT.
ALFRED B. BELL.
